MUSICAL INSTRUMENT

Vincent Lyle Badkin, Campgaw, N. J.

Application January 27, 1950, Serial No. 7,520

Term of patent 7 years

(Cl. D56—1)

To all whom it may concern:

Be it known that I, Vincent Lyle Badkin, a citizen of the United States of America and a resident of Campgaw, in the county of Bergen and State of New Jersey, have invented a new, original, and ornamental Design for a Musical Instrument, of which the following is a specification, reference being had to the accompanying drawing, forming a part thereof.

In this drawing:

Figure 1 is a front elevational view of the musical instrument, showing my new design; and

Figure 2 is a side elevational view of the same. The rear of the instrument is plain.

I claim:

The ornamental design for a musical instrument, as shown and described.

VINCENT LYLE BADKIN.
